FABRICATED SKI

Danforth Holley, 209 Lake Shore Road,
Grosse Pointe Farms, Mich.

Filed July 28, 1958, Ser. No. 751,371

13 Claims. (Cl. 280—11.13)

This invention relates generally to a fabricated ski, and refers more particularly to a ski having improved metal edge strips mounted in a unique manner thereon.

Formerly, skis were made entirely of wood. Such skis were found to be subject to deterioration of their bottom corners due to pressures and bumps applied thereto in normal use. Therefore, metal edge strips were applied to the lower surfaces of skis at the outer edge thereof to reduce the deterioration of the lower corners of the skis. It has also been determined that certain plastic materials produce more desirable sliding surfaces for skis than wood does. So the lower surfaces of skis are often coated with plastic materials.

In the past difficulties have been encountered in the application of these metal edge strips and plastic coatings to skis. From an operational standpoint it is desirable to apply the metal edge strips to the lower surface of the ski and then plastic coat the lower surface of the ski and most of the edge strip. This construction in the past, has produced feather edges in the plastic coating material which are difficult to permanently fix in place.

Also, when the ski is flexed longitudinally as it necessarily is in use, the metal edges in the past have tended to separate the plastic coating from the ski. Furthermore, recessing the wood portion of a ski for installation of edge strips has often produced weak sections and objectionable feather edges in the runner of the ski.

Also, it has been found that skis having metal edge strips on the bottom corners thereof are less likely to slip sideways in use than are skis having wood bottom corners for the reason that sharper corners can be produced and maintained on the metal strips. However, the provision of metal edge strips having a vertical exposed side and a horizontal exposed bottom surface has not completely solved the problem of objectionable sideways movement in the use of skis.

Therefore, one of the essential objects of this invention is to provide a ski with an edge strip that does not tend to destroy the bond between the wood and plastic parts of the ski when the ski is flexed.

Another object is to provide a ski with an inclined edge strip without producing feather edges on the other elements of the ski.

Another object is to provide edges for a ski composed of a plurality of separate edge strip sections which will allow bonding between the wood and plastic parts of the ski between individual sections of the edge strips and at intermediate points along the edge strip sections.

Another object is to provide edge strips for a ski which will decrease skidding of the ski when the ski is in use.

Another object is to provide edge strips for a ski which are inclined from the lower corner toward the middle of the ski runner.

Another object is to provide a ski with metal edge strips which have the outside edge portions thereof turned down to form lower corners for the ski.

2

Another object is to provide a ski with metal edge strips which have the outside edge portions thereof turned down to form lower corners for the ski, the lower corners having an acute included angle.

5 Another object is to provide a ski having metal edge strips, which ski is simple in construction, easy to manufacture, and efficient in use.

Other objects and features of the invention will become apparent as the description proceeds, especially when 10 taken in conjunction with the accompanying drawings, illustrating preferred embodiments of the invention, wherein:

Figure 1 is a partial cross-section of a ski having an edge strip according to the invention mounted thereon.

Figure 2 is a bottom view of a ski having edge strips thereon according to the invention.

Figure 3 is a side view of a ski having edge strips thereon according to the invention.

Figure 4 is a plan view of an edge strip of the invention.

Figure 5 is a plan view of an edge strip of the invention showing representative modifications which can be included therein.

Figure 6 is a cross-section of the edge strip shown in 25 Figure 4 taken along the line 6—6.

This invention consists of providing a ski generally designated on the drawing as 2, which has a wooden runner section 4 and a plastic bottom coating 6 with a plurality of end abutted metal edge strips 10. The edge strips 10 are positioned end to end at the bottom edges of the ski 2 and form acute angled sharp bottom corners 12 for substantially the entire length of the ski.

According to the invention the edge strips 10 are positioned between the wooden runner 4 and the plastic bottom coating 6 and for a major portion of their width are inclined at an angle 14 of approximately ten degrees to the bottom surface 15 of the ski 2. The outside edge portions 16 of the strips 10 are turned down along a longitudinal fold line 17 to make an angle 18 of approximately 167½ degrees with the side 20 of runner 4, as indicated in Figure 1. Edge strips 10 formed and positioned as indicated do not materially affect the bond between the wood runner 4 and the plastic bottom coating 6 when the ski 2 is flexed longitudinally and they greatly reduce skidding of the ski when it is in use.

Also, according to the invention the individual edge strip sections 10 are provided with means to increase the bond between the wood runner 4 and the plastic coating 6 in the vicinity of the sections 10. Increased bond in this vicinity is desirable as most bonding failures between the plastic bottom coating 6 and the other members of skis having metal edge strips occur in the vicinity of the edge strips.

The major unit of the ski 2 shown in the drawings is the wooden runner 4. The composition and general form of such runners is well known and will not therefore be discussed here. The bottom and lower side portions of the runner 4 of this invention are believed to be unique and therefore will be described in detail. 55 The bottom surface 22 of runner 4 is inclined upwardly for a short distance at an angle of approximately ten degrees with the non-inclined central bottom surface 24. The inclined surface 22 as shown in Figure 1, extends from the lower corner of the runner and toward the center of the ski. An inclined surface 22 is provided on both sides of the bottom of runner 4. The inclined surfaces 22 extend as shown in Figures 2 and 3 for substantially the entire length of the ski 2. Inclined surfaces 22 are terminated at surfaces 26 which are also provided on both sides of the bottom of runner 4 and which connect surfaces 22 and 24. Surfaces 22 and 26 may be formed in the bottom of runner 4 by a belt sanding oper-

ation. It will be noted that the forming of surfaces 22 and 26 in the bottom of runner 4 does not produce feather edges or other particularly weak configurations in the runner.

Individual edge strips 10, best shown in Figures 4 and 5, consist of short strips of metal having the particular cross-section shown in Figure 6. One edge portion 16 of the individual strips 10 is bent at an angle to the main portion thereof so that when the strips 10 are attached to the surface 22 with the bent down edge portion of the strips 10 positioned at the lower corner of runner 4 the side 20 of runner 4 makes an angle 18 of approximately 167½ degrees with the bent down portion of edge strips 10, as shown in Figure 1. The outside edge 27 of the bent down portion 16 of edge strip 10 therefore forms an acute angle with the bottom surface of ski 2. With such construction, when ski 2 skids while in use acute angled edge 12 will bite into the sliding surface and will be forced further into the sliding surface as skidding continues by inclined surface 27, thereby greatly restricting the skidding movement.

Edge strips 10 are also provided with countersunk holes 28 and screws 29 to facilitate the screw attachment of strips 10 at the lower corners of runner 4. The ends of edge strips 10 are inclined as shown in Figure 4 and 5 to provide for bonding of the plastic bottom coating 6 to the wood runner 4 between the ends of strips 10 when they are placed end to end to form a complete edge for ski 2. Edge strips 10 may be further provided with recesses 30 as indicated in Figure 5, or holes 31 as indicated in Figure 6 to allow more area for bonding the bottom coating 6 to the wood runner 4 in the vicinity of the metal edge strips 8.

The bottom coating 6 of the runner 2 is bonded to both the wooden runner 4 and the metal edge strips 10. The lower surface 32 of the bottom coating 6 is level and forms the bottom or sliding surface of ski 2. The upper surface 34 of the bottom coating 6 follows the contour of the lower surface of runner 2 with edge strips 10 attached thereto. As shown in Figure 1, the bottom coating 6 has relatively thick edges capable of being firmly fixed in place. It should also be noted that the edge strips 10 have no coating thereon at the extreme lower corners of the ski 2.

The materials from which the members of ski 2 are formed are conventional. The runner 4 may be made of wood, either solid or laminated as desired. The edge strips 8 may be made of spring steel. Polyester plastics or epoxy resins with magnesium filler may be used as a bottom coating for ski 2. The materials indicated are only illustrative of the invention and it is not intended to restrict the invention thereto.

In use ski 2 with edge strips 10 attached thereto will be prevented from slipping sideways to a great extent by the metal edge strips 10. Because of the angle 18 of the surface 27 between the outside of the bent down portion of edge strips 10 and the sides of runner 4, the ski 2 will tend to dig into the surface on which it is skidding thereby halting sideways slipping. Also, due to the particular angle 14 at which the edge strips 10 are set in ski 2, when the ski 2 is flexed in use the strips 10 tend to force the plastic coating 6 toward the center of the ski where the plastic coating is thick and well bonded to wood runner 4 instead of tending to force the plastic coating away from the runner 4 in the area of the edge strips as has been the case with past metal edge strips.

The drawing and the foregoing specification constitute a description of the improved fabricated ski in such full, clear, concise and exact terms as to enable any person skilled in the art to practice the invention, the scope of which is indicated by the appended claims.

What I claim as my invention is:

1. A ski comprising a runner substantially rectangular in cross section having the lower surface thereof inclined upward for a short distance from each bottom corner

toward the middle of said runner, a covering material bonded to the lower surface of said runner, and elongated edge strips attached to said inclined surfaces between said runner and said covering material said edge strips extending to the sides of said runner, the outside edge portion of said edge strips being turned down along a longitudinal fold line to form an obtuse angle with the sides of said runner, the extreme outer edge of the edge strips forming an acute angle with the lowermost face of the outside edge portion of the edge strips, whereby sideways slipping of said ski in use is restricted, the lowermost surface of the outside edge portion of the edge strips together with the covering material forming the running surface of the ski.

2. A ski comprising a runner substantially rectangular in cross section having substantially vertical sides and also having the lower surface thereof inclined upward for a short distance from the sides toward the middle of said runner, a covering material bonded to the lower surface of said runner, and elongated edge strips attached to said inclined surfaces between said runner and said covering material, said edge strips extending to the sides of said runner, the outside edge portion of said edge strips being turned down along a longitudinal fold line to form an angle of approximately 167½ degrees with the vertical sides of said runner, the extreme outer edge of the edge strips forming an angle of approximately 77½ degrees with the lowermost face of the outside edge portion of the edge strips, whereby sideways slipping of said ski in use is restricted, the lowermost surface of the outside edge portion of the edge strips together with the covering material forming the running surface of the ski.

3. A ski comprising a runner substantially rectangular in cross section having substantially vertical sides and also having the lower surface thereof inclined upward for a short distance from the sides toward the middle of said runner, a covering material bonded to the lower surface of said runner, and elongated edge strips attached to said inclined surfaces between said runner and said covering material, said edge strips extending to the sides of said runner, the outside edge portion of said edge strips being turned down along a longitudinal fold line to form an angle of approximately 167½ degrees with the vertical sides of said runner, the extreme outer edge of the edge strips forming an angle of approximately 77½ degrees with the lowermost face of the outside edge portion of the edge strips, whereby sideways slipping of said ski in use is restricted, the lowermost surface of the outside edge portion of the edge strips together with the covering material forming the running surface of the ski, the inside surface of said turned down edge portion of said edge strips being of substantial height and forming a relatively large angle with the running surface of said ski, said lower surface covering material butting against the inside surface of the turned down edge portion of said edge strips to eliminate covering material feather edges.

4. A ski comprising a runner substantially rectangular in cross section having substantially vertical sides and also having the lower surface thereof inclined upward for a short distance from the sides toward the middle of said runner, a covering material bonded to the lower surface of said runner, and elongated edge strips attached to said inclined surfaces between said runner and said covering material, said edge strips extending to the sides of said runner, the outside edge portions of said edge strips being turned down along a longitudinal fold line to form an angle of between 165 and 170 degrees with the vertical sides of said runner, the extreme outer edge of the edge strips forming an angle of between 75 and 80 degrees with the lowermost face of the outside edge portion of the edge strips, whereby sideways slipping of said ski in use is restricted, the lowermost surface of the outside edge portion of the edge strips together with the covering material forming the running surface of the ski.

5. A ski comprising a runner substantially rectangular in cross section having substantially vertical sides and also having the lower surface thereof inclined upward for a short distance from the sides toward the middle of said runner, a covering material bonded to the lower surface of said runner, and elongated edge strips attached to said inclined surfaces between said runner and said covering material, said edge strips extending to the sides of said runner, the outside edge portion of said edge strips being turned down along a longitudinal fold line to form an angle of more than 160 degrees with the vertical sides of said runner, the extreme outer edge of the edge strips forming an acute angle with the lowermost face of the outside edge portion of the edge strips, whereby sideways slipping of said ski in use is restricted, the lowermost surface of the outside edge portion of the edge strips together with the covering material forming the running surface of the ski.

6. A ski comprising a runner substantially rectangular in cross section having substantially vertical sides and also having the lower surface thereof inclined upward for a short distance from the bottom corners toward the middle of said runner at an angle of approximately 10 degrees from the otherwise horizontal bottom, a covering material bonded to the lower surface of said runner, and elongated edge strips attached to said inclined surfaces between said runner and said covering material, said edge strips having the outside edge portions thereof turned down along a longitudinal fold line to form an angle of approximately 167½ degrees with the vertical sides of said runner, the extreme outer edge of the edge strips forming an angle of approximately 77½ degrees with the lowermost face of the outside edge portion of the edge strips, whereby skidding of said ski in use is restricted, the lowermost surface of the outside edge portion of the edge strips together with the covering material forming the running surface of the ski.

7. A ski comprising a runner substantially rectangular in cross section having substantially vertical sides and also having the lower surface thereof inclined upward for a short distance from the bottom corners toward the middle of said runner at an angle of approximately 10 degrees from the otherwise horizontal bottom, a covering material bonded to the lower surface of said runner, and elongated edge strips attached to said inclined surfaces between said runner and said covering material, said edge strips having the outside edge portions thereof turned down along a longitudinal fold line to form an angle of approximately 167½ degrees with the vertical sides of said runner, the extreme outer edge strip forming an angle of approximately 77½ degrees with the lowermost face of the outside edge portion of the edge strips, whereby skidding of said ski in use is restricted, the lowermost surface of the outside edge portion of the edge strips together with the covering material forming the running surface of the ski, the inside surface of said turned down edge portion of said edge strips being of substantial height and forming a relatively large angle with the running surface of said ski, said lower surface covering material butting against the inside surfaces of the turned down edge portion of said edge strips to eliminate covering material feather edges.

8. A ski comprising a runner substantially rectangular in cross section having substantially vertical sides and also having the lower surface thereof inclined upward for a short distance from the bottom corners toward the middle of said runner at an angle of approximately 10 degrees from the otherwise horizontal bottom, a covering material bonded to the lower surface of said runner, and elongated edge strips having abutting ends attached to said inclined surfaces between said runner and said covering material, said edge strips having recesses extending laterally inwardly from the inner edge thereof and also having the ends of abutting strips inclined so that the coating material may be bonded to said runner at said

recesses and between the ends of said strips, said edge strips, said edge strips also having the outside edge portions thereof turned down along a longitudinal fold line to form an angle of more than 160 degrees with the vertical sides of said runner, the extreme outer edge of the edge strips forming an acute angle with the lowermost face of the outside edge portion of the edge strips, whereby sideways slipping of said ski in use is restricted, the lowermost surface of the outside edge portion of the edge strips together with the covering material forming the running surface of the ski.

9. A ski comprising a runner substantially rectangular in cross section having substantially vertical sides and also having the lower surface thereof inclined upward for a short distance from the bottom corners toward the middle of said runner at an angle of approximately 10 degrees from the otherwise horizontal bottom, a covering material bonded to the lower surface of said runner, and elongated edge strips having abutting ends attached to said inclined surfaces between said runner and said covering material, said edge strips having recesses extending laterally inwardly from the inner edge thereof and also having the ends of abutting strips inclined so that the coating material may be bonded to said runner at said recesses and between the ends of said strips, said edge strips also having the outside edge portions thereof turned down along a longitudinal fold line to form an angle of between 165 and 170 degrees with the vertical sides of said runner, the extreme outer edge of the edge strips forming an angle of approximately 77½ degrees with the lowermost face of the outside edge portion of the edge strips, whereby sideways slipping of said ski in use is restricted, the lowermost surface of the outside edge portion of the edge strips together with the covering material forming the running surface of the ski.

10. A ski comprising a runner of substantially rectangular cross section and longitudinally extending edge strips secured to said runner along the lower corners thereof, said edge strips extending inwardly and upwardly from the lower corners of said runner, the outer edge portion of said edge strips extending outward beyond the sides of said runner and being angled downward along a longitudinal fold line at a substantial angle, the extreme outer edge of the edge strips forming an acute angle with the lowermost face of the outside edge portion of the edge strips to restrict sideways slipping of said ski in use, the lowermost surface of the outside edge portion of the edge strips together with the bottom surface of the runner forming the running surface of the ski, the inside surface of said turned down edge portion of said edge strips being of substantial height and forming a relatively large angle with the running surface of said ski eliminating feather edges on said runner and tending to compress the lower portion of said ski on longitudinal flexing thereof in use.

11. A ski comprising a runner of substantially rectangular cross section and longitudinally extending edge strips secured to said runner along the lower corners thereof, said edge strips extending inwardly and upwardly from the lower corners of said runner at an angle of approximately 10° with the bottom of said runner, the outer edge portion of said edge strips extending outward beyond the sides of said runner and being angled downward along a longitudinal fold line at an angle of approximately 165° to the sides of said runner, the extreme outer edge of the edge strips forming an angle of approximately 77½ degrees with the lowermost face of the outside edge portion of the edge strips to restrict sideways slipping of said ski in use, the lowermost surface of the outside edge portion of the edge strips together with the bottom surface of the runner forming the running surface of the ski, the inside surface of said turned down edge portion of said edge strips being of substantial height and forming a relatively large angle with the running surface of said

ski eliminating feather edges on said runner and tending to compress the lower portion of said ski on longitudinal flexing thereof in use.

12. A ski comprising a runner of substantially rectangular transverse cross section and longitudinally extending edge strips secured to said runner along the lower corners thereof, said edge strips having at least a lower inside surface extending diagonally inwardly and upwardly from the lower corners of said runner, the outer edge portion of said edge strips being angled downward along a longitudinal fold line at a substantial angle, the extreme outer edge of the edge strips forming an angle of not more than ninety degrees with the lowermost face of the outside edge portion of the edge strips to restrict sideways slipping of said ski in use, the lowermost surface of the outside edge portion of the edge strips together with the bottom surface of the runner forming the running surface of the ski, the inside surface of said turned down edge portion of said edge strips being of substantial height and forming a relatively large angle with the running surface of said ski eliminating feather edges on said runner and tending to compress the lower portion of said ski on longitudinal flexing thereof in use.

13. A ski comprising a runner of substantially rectangular cross section, edge strips secured to said runner at each lower corner thereof, each of said edge strips including a lowermost surface extending inwardly of the runner along the bottom surface of the runner from the

corner thereof to form part of the running surface of the ski, and a first inner surface extending upward from the inner edge of the lowermost surface a substantial distance and making a substantial angle with the lowermost surface to eliminate feather edges on the running surface of the ski, said edge strips also including a second inner surface extending upwardly and inwardly of the runner from the upper edge of the first inner surface whereby the edge strips tend to compress the lower portion of the ski on longitudinal flexing of the ski, and an outer surface extending generally upward from the outer edge of the lowermost surface making an angle of not more than ninety degrees therewith to restrict sideways slipping of the ski in use, and a coating material secured to the lower surface of said runner between said edge strips which forms the running surface of the ski in conjunction with the lowermost surface of the edge strips.
